UNITED STATES PATENT OFFICE

97,019

DESIGN FOR A MOTORCYCLE

Frank H. Sedivy, Verdигre, Nebraska

Application May 16, 1935, Serial No. 56,867

Term of patent 14 years

To all whom it may concern:

Be it known that I, Frank H. Sedivy, a citizen of the United States, residing at Verdигre, in the county of Knox and State of Nebraska, have invented a new, original, and ornamental Design for Motorcycles, of which the following is a specification, reference being had to the accompanying drawing, forming part thereof.

I claim:

The ornamental design for a motorcycle, as shown.

FRANK H. SEDIVY.
